UNITED STATES PATENT OFFICE.

BURTON U. HILLS, OF CHICAGO, ILLINOIS.

TIMING DEVICE AND PROCESS OF MANUFACTURING THE SAME.

Application filed February 11, 1921. Serial No. 444,174.

My invention belongs to that general class of devices known as timers or timing devices for internal combustion engines, and an improved process of manufacturing the same. As is well known, timing devices, or timers as they are generally known, are adapted for successively conducting an electrical current to the several sparking devices from a common conductor, and thereby igniting the charges in the cylinders and energizing the engine. The invention has among its objects the production of a device of the kind described that is simple, convenient, compact, durable, efficient, reliable and satisfactory for use wherever found applicable. It also has particularly as an object the production of a device which may be economically manufactured, and which will not easily get out of order or be affected by weather conditions. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of my improved device mounted for use;

Fig. 2 is a view in elevation of my improved device looking from the rear side thereof;

Fig. 3 is a cross sectional view taken substantially on line 3—3 of Fig. 2;

Fig. 4 is a cross sectional view taken substantially through the operating shaft and sleeve, illustrating the retaining pin connecting the parts together; and

Fig. 5 is a perspective view of a contact and conducting member carried by the rotor.

Referring to the drawings, in which the preferred embodiment of my invention is shown, 1 represents the timer driving shaft driven in the usual or any preferred manner, not necessary to describe in detail, having mounted thereon a rotor 2 formed of fiber or other non-conducting material, as will be hereinafter described. The rotor is

preferably circular in form, and is mounted upon a sleeve 3 formed of brass or other suitable electric conducting material, which is in turn secured to the shaft 1 in any preferred manner. As illustrated, the sleeve is detachably secured on and prevented from rotating on the shaft by means of a pin 5, which projects through a slot or the equivalent opening in one wall of the sleeve 3 into the shaft, the sleeve projecting beyond the face of the disk a slight distance, as most clearly shown in Fig. 3 of the drawings. A cap or cover 6, preferably of metal, encloses the projecting end of the sleeve 3 and pin 5, retaining the pin in place, and is preferably of a length to engage with the face of the body of the rotor, the extreme edge of the cap being preferably flanged so as to lie against the rotor. The cap 6 is maintained in position on the shaft and against the rotor, maintaining the rotor firmly in place, by means of a suitable nut 7 or equivalent means mounted upon the extreme end of the shaft.

This construction is not only particularly simple and inexpensive, but the rotor is operatively and securely maintained in a predetermined position upon the shaft both circumferentially and longitudinally of the end of the sleeve, being positively held against the shoulder upon the shaft, as shown. This construction also requires that the rotor be always applied in a predetermined manner, as will be hereinafter described, thereby preventing improper assembly of the parts.

In the form of device shown, the rotor 2 is circular in form, as previously mentioned, or that is, substantially cylindrical, the outer edge of which has a face of non-conducting material except at the point where a contact member is positioned. This electric conductor or contact member consists in the preferred construction of a sheet metal plate 9, formed with an extension 10 through which an opening 11 is provided of a size to closely fit the sleeve. The same may be secured on the sleeve in any suitable manner, and in the construction shown, I have provided a lug 12 adapted to fit in a recess in the flange 3' of the sleeve. The flange 3' maintains the plate 9 in contact with the rotor or disk, while the lug 12 is in engagement with the notch therein.

prevents relative rotation of the sleeve and the plate. The plate 9 is flanged or bent over as at 13 at the outer end so as to overlie the edge of the disk, the extreme edge being 5 flanged as at 14 to overlie the opposite face of the rotor. As most clearly shown in Figure 2, the disk is recessed at its edge so that the portion 13, which conforms to the periphery of the rotor, is substantially flush 10 with the face of the edge.

I prefer to construct the disk or rotor 2 of a body of suitable non-conducting material such as bakelite or preferably a specially prepared and treated fiber possessing 15 great hardness and rigidity without sacrificing any of its non-conducting qualities. I might say that I prefer generally to use a fiber made up of cotton, worked into paper. I also prefer to use the fiber in substantially 20 thin disks or sheets or laminæ, which are arranged face to face and forced together under high pressure so as to provide substantially a unitary structure. Either before or 25 after the pressure forming of the disk or rotor, I suitably size, treat or impregnate the fiber so that it is substantially moisture-proof. This treatment may consist of any suitable lubricant or lubricating oils or a combination of oils. Obviously, any additional 30 binder desired may be arranged between the laminæ, but generally the sizing or lubricant will serve as a binder, and the great pressure applied in forming of the rotor will cause the parts to be united permanently and form 35 substantially a unitary structure without additional binding means. By using the laminæ, the grain or layers of fiber or other material forming the rotor extend transversely of the disk or rotor, the same forming 40 a substantially uniform structure of great hardness and durability throughout. The same may be shaped by suitable dies and a hole punched or cut through in any desired manner, either before, during or after 45 the forming. After the hole is provided, the sleeve 3 is positioned and the plate 9 forced over the edge and down to overlie the opposite face of the disk. After the disk is thus constructed, I place the same in a suitable 50 grinder or equivalent machine, and carefully finish the edge, including the contact face 13, it being found desirable to finish the edge as accurately and as smoothly as possible so that the circumference or periphery 55 is at all points uniformly distant from the axis of rotation and perfectly smooth.

The contact member on the rotor is arranged to cooperate with the desired number of contact points or members 17 as the 60 rotor is driven. As shown, I provide a casing 16 of the desired size, shape and material, which normally incloses the rotor and prevents the admission of dust, dirt, moisture, grease, etc. thereto, the same being 65 maintained in place, in the construction

shown, by its engagement with the body of the engine or other supports carrying the shaft 1 and a member 20 mounted on an adjacent part 21. Member 20 is provided with a protruding part arranged to engage 70 in a depression in the end of the cover of the casing, it being understood, however, that the particular construction of the casing and the method of supporting the same may be varied as desired. The construction illustrated, however, permits the casing to be shifted or adjusted, as will be hereinafter described. A bracket 19 and operating rod 19' afford means for adjusting the casing. Arranged on the casing are the desired number 80 of binding posts 15, the number depending upon the particular use for which the device is intended to be used. For use on an internal combustion engine, I provide one binding post for each spark plug, or 85 other igniting device, the contacts on the spark plugs being connected therewith by suitable wires or the equivalents, in the usual manner. The binding posts extend within the casing, and are electrically connected 90 with spring members 18, carrying the contacts or brush members 17. The springs extend in the direction of the rotation of the rotor, and serve the double purpose of maintaining the contact members 17 in engagement 95 with the surface of the disk, and at the same time as electrical conductors connecting the members 17 with the binding posts. When the casing or cover is of metal construction, the binding posts are insulated 100 from the casing by the washers 23 on the inside and similar washers on the outside, of suitable insulating material, and I also prefer to provide a strip 22 of non-conducting material around the interior of the shell. 105

The operation of the device may be briefly described as follows: Assuming that the timer is applied substantially as shown, the binding posts being connected with the ignition apparatus and the shaft 1 grounded or 110 connected with the source of electrical energy, as the rotor 2 is driven by the shaft, the contact member 9 at its face portion 13 successively contacts with the several contact members 17 so that the several circuits through the several binding posts are 115 successively closed and opened. If the casing is shifted or adjusted, obviously the time of contact with the members 17 and 9 is varied, being either retarded or advanced 120 depending upon the adjustment made. With this construction, the members 17 are at all times maintained in perfect contact with the face of the rotating rotor, which as before mentioned, is accurately formed. It will 125 be particularly noted by referring to Fig. 2 that each of the springs 18 extends from the end where the contact member 17 is located to a point toward the opposite end, substantially tangential to the finished edge or pe- 130

riphery of the rotor. The casing may be shifted in either direction without danger of the contacts 17 engaging or ruffling up the face of the disk. This construction also requires less pressure to be put on the contact 17 in order to maintain the same in place, and there is consequently less wear on the parts.

By constructing the rotor in the manner 10 described, of layers of fiber or the like suitably treated and formed, a substantially uniform structure is secured, any difference in hardness or softness and tendency to wear being balanced by the hardness or softness 15 of the adjacent layers in the rotor, which is impervious to water or moisture, and may be polished to a high degree, the same being maintained polished by the contacts 17 drawing over the same with the substantially 20 light pressure referred to.

The timer may be easily and conveniently disassembled by simply swinging over the arm 20 and removing the cover 16. The points of contact between the member 17 and 25 the plate 9 may be easily cleaned if necessary. The rotor may be conveniently and easily removed by merely taking off the nut 7. Owing to the fact that the rotor is impregnated in the manner described, the same 30 does not take up oils or grease irregularly about the surface, as would be the case where a porous body was employed.

Extensive use and continuous hard tests have proved the rotor to be extremely hard 35 and durable, with but slight wear on the contacts and face of the rotor. The rotor to a certain extent lubricates the contacts 17, and reduces wear thereon, so that they are of long life and seldom require to be renewed. 40 They also show that the device is not at all affected by moisture or grease or oil, and that a particularly efficient operation of the engine is secured.

Having thus described my invention, it is 45 obvious that various immaterial modifications may be made in the same without departing from the spirit of my invention; hence I do not wish to be understood as limiting myself to the exact form, construction, 50 arrangement and combination of parts herein shown and described, or uses mentioned.

What I claim as new and desire to secure by Letters Patent is:

1. In an ignition timer, a rotor comprising 55 a disk of insulating material having a peripheral slot therein, and a central bore therethrough, a metallic bushing in said bore, a metallic contact member having an arcuate portion in said peripheral slot, flush 60 with the periphery of the disk and overlying said disk at its sides, one of said overlying portions being radially extended inwardly of the disk and encircling said bushing, said bushing having a recess therein, and said 65 radially extended portion of the contact

member having a projection thereon engageable in said recess to prevent relative rotational movement therebetween.

2. In an ignition timer, a rotor comprising 70 a disk of insulating material having a peripheral recess therein and being axially bored, a metallic bushing in said bore, said metallic bushing having an annularly shouldered enlarged end portion, a metallic contact member having an arcuate portion 75 flush in said peripheral slot and overlying said disk at its sides, one of said overlying portions of the member being radially extended inwardly of the periphery and formed with a ring at the end encircling the 80 reduced portion of the bushing, whereby said ring portion of the contact member may be clamped between the face of the disk and the annular shoulder of the bushing, and means between said bushing and contact 85 member to prevent relative rotational movement therebetween.

3. In combination with a rotatable shaft, a sleeve carried by the shaft, an outwardly extending flange formed on the sleeve and 90 provided with a recess therein, a rotor carried by the sleeve, and means carried by the rotor and engageable in the recess of the flange for preventing rotatable movement of the rotor independently of the sleeve. 95

4. In combination with a rotatable shaft, a sleeve carried by the shaft, an outwardly extending flange formed on the sleeve and provided with a recess therein, a rotor carried by the sleeve, a contact member carried 100 by the rotor, and a lug formed on the contact member and engageable in the recess of the sleeve flange for preventing rotatable movement of the rotor independently of the sleeve. 105

5. In an ignition device, a disk of insulating material and a contact member at one side of said disk, having a part extending across and with its outer face flush with the periphery of said disk, in combination 110 with a tubular sleeve extending centrally through said disk and said contact member, whereby said sleeve, said disk, and said contact member are connected to form a unitary device locked against independent rotary 115 movement.

6. In an ignition device, a disk of insulating material and a metal contact member at one side of said disk having a part extending across and with its outer face 120 flush with the periphery of said disk, in combination with a tubular sleeve extending centrally through said disk and contact member whereby said sleeve, said disk and said contact member are connected as a unitary structure and rotate as such. 125

7. In an ignition device, a disk of insulating material and a metal contact member at one side of said disk having a part 130 extending across with its outer face flush

with the periphery of said disk, in combination with a tubular sleeve extending centrally through said disk and said contact member, and cooperating means upon said sleeve and said contact member adapted to prevent rotary movement between them whereby said sleeve, said disk and said con-

tact member are connected to constitute a unitary structure adapted to rotary movement as such.

10

In testimony whereof, I have hereunto signed my name.

BURTON U. HILLS.
